UNITED STATES PATENT OFFICE.

SAMUEL A. NELSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR LOOMS.

Application filed May 29, 1926. Serial No. 112,642.

This invention relates to automatic looms in which provision is made for replenishing any one of a series of shuttles which may carry different kinds or colors of weft. The invention is more particularly designed for use in a so-called "pick and pick" loom in which a plurality of shifting shuttle boxes are provided at each end of the lay and in which any one of the shuttles may be put 5 in action for a single pick or for a plurality of picks in accordance with the lay-out of the weaving pattern chain.

One general object of my invention is to provide improved mechanism by which a selected weft carrier may be transferred 15 horizontally into a corresponding shuttle in any one of a plurality of shifting shuttle boxes at the magazine end of the loom.

A further object is to provide mechanism 20 by which such a transfer may take place during the shifting of the shuttle boxes to operative position, thus securing a longer time interval in which to make the transfer.

Other features of my invention relate to 25 the provision of an improved transfer-controlling mechanism; to the provision of novel and improved mechanism for selectively positioning the transerrer and for thereafter moving the transerrer with the 30 magazine and shuttle boxes; to certain improvements in the pattern mechanism by which the weft replenishment is controlled, and to other arrangements and combinations 35 of parts which will be hereinafter described and more particularly pointed out in the appended claims.

A preferred form of the invention is shown in the drawings, in which

Fig. 1 is a side elevation of portions of 40 a loom embodying my improvements;

Fig. 2 is an enlarged side elevation of the magazine and replenishing mechanism;

Fig. 3 is a sectional plan view of the 45 replenishing mechanism, taken along the line 3-3 in Fig. 2;

Fig. 4 is a plan view of certain parts, looking in the direction of the arrow 4 in Fig. 2;

Fig. 5 is a partial side elevation of the 50 left hand end of the loom;

Fig. 6 is a sectional plan view, taken along the line 6-6 in Fig. 5.

Fig. 7 is a plan view of a portion of the pattern mechanism;

Fig. 8 is a side elevation of the same parts, 55 looking in the direction of the arrow 8 in Fig. 7;

Fig. 9 is a plan view of a portion of the drop box and magazine controlling mechanism;

Fig. 10 is a side elevation, looking in the direction of the arrow 10 in Fig. 9;

Fig. 11 is a front elevation, looking in the direction of the arrow 11 in Fig. 10;

Fig. 12 is a detail sectional side elevation, 65 of a portion of the magazine; and

Fig. 13 is a detail sectional plan view, taken along the line 13-13 in Fig. 1.

General construction.

Referring to the drawings, I have shown portions of a loom of the "pick and pick" type having a loom frame 20 with a magazine M (Fig. 1) and weft replenishing mechanism R mounted at the right hand end of 75 the loom and having drop boxes 21 mounted for vertical movement on a lifter rod 22, also at the right hand end of the loom. The boxes 21 are carried by the lay 23, mounted upon the usual swinging supports or swords 24, and actuated through links 25 from the usual crank shaft (not shown).

At the opposite or left hand end of the lay 23, a corresponding number of the usual drop boxes are provided. These left hand boxes are of the regular commercial type and are not shown in the drawings, but portions of the control and actuating mechanism for these boxes are shown in Figs. 5 and 6 and are indicated generally by the letter D.

Pattern mechanism P (Figs. 5 and 7) is provided for actuating the shuttle boxes in accordance with the design of the fabric and also for controlling the positions of the magazine and transfer mechanism.

The magazine M (Fig. 2) is provided with a series of superposed compartments 30, each having a rearward outlet or discharge opening 31, and a transerrer 32 is mounted for vertical movement into alignment with any selected discharge opening 31.

Mechanism is provided by which the transerrer is always positioned opposite the magazine compartment corresponding to the

shuttle which is about to become active, and the pattern mechanism is so arranged that the selective movement of the transferrer takes place before the corresponding movement of the drop boxes.

Additional mechanism is also provided for thereafter moving both the transferrer and magazine vertically as the boxes are shifted, so that the magazine is in a position to transfer a bobbin to the shuttle during the movement of the shuttle boxes.

Magazine construction.

The weft carrier magazine, as previously stated, is of a special construction and as shown in the drawings comprises three superposed compartments 30 (Fig. 2) formed in a magazine frame 33 and having a rearward discharge opening 31 from each magazine compartment. A light spring 34 (Fig. 12) yieldingly prevents rearward escape of the bobbins through each opening 31, except when forcibly ejected therefrom by the transferrer 32.

Each compartment is shown as providing storage for three weft carriers of a particular kind or color. As the loom shown in the drawings is particularly designed for use in weaving silk, a very much smaller storage capacity is permissible than would be required for weaving cotton or other material in which the bobbins are quickly exhausted and must be frequently replenished. In the silk loom, the weft or filling is so fine that a bobbin or weft carrier will commonly run for several hours before it becomes exhausted and requires replenishment.

The magazine M is provided with a guide-way 36 (Fig. 4) at one end for the butts of the bobbins and with a narrower guide-way 37 at the opposite end for the tips of the bobbins. The magazine frame 33 is mounted in a support 40 (Fig. 2) secured to the upper end of a dove-tailed slide 41 (Fig. 3) mounted for vertical movement in guide-ways 42 in a stand 43 mounted in fixed position on the loom frame 20. A rack bar 44 is secured to the side of the member 41 and is engaged by a pinion 45 mounted on a stud 46 which is rotatably mounted in the upper end of a link 47. The lower end of the link 47 is pivoted to an arm 48 (Fig. 13) on a rock shaft 49 and is controlled from the pattern mechanism P by connections to be described.

The stud 46 extends outward through a slot 50 in a cover or casing 43^a, which slot permits the stud and its pinion 45 to be moved freely vertically.

Replenishing mechanism.

I will now describe the replenishing mechanism by which the transferrer 32 is selectively positioned and actuated to transfer a

weft carrier from one of the magazine compartments to a substantially exhausted shuttle.

The transferrer 32 (Fig. 4) is mounted on the slide 52 movable horizontally in guide-ways 53 secured to the upper end of a dove-tailed support 54 (Figs 2 and 3) which is vertically slidable in guide-ways 55 in the stand 43 previously described.

A rack bar 56 is secured to one face of the sliding support 54 and is engaged by a pinion 57 mounted on a stud 58 extending outwardly through a slot 59 in the stand 43 and pivotally connected to the upper end of a link 60. The lower end of the link 60 (Figs. 1 and 13) is pivoted to a second arm 61 on the rocking member 49 previously described.

The arms 48 and 61 of the member 49 are preferably of the same length, and the pinions 45 and 57 are of the same size, consequently movement of the member 49 will cause the transferrer 32 to move in one direction while the magazine M moves in the opposite direction and for the same distance. In this manner, the transferrer may be quickly positioned opposite any selected magazine compartment.

The transferrer slide 52 (Fig. 4) is provided with a stud 63 extending to the left through an elongated vertical slot 64 (Fig. 1) in an actuating head 65. The head 65 is mounted at the rear end of a slide or plunger 66 (Fig. 2) supported in a bearing 67 formed on a fixed bracket 68. The plunger 66 has an axial recess 69 in which an actuating rod 70 is freely slidable.

The rod 70 is pivoted at 71 to the upper end of a lever 72 pivoted on a bracket 73 and having its lower end pivotally connected at 74 to a link 75 (Fig. 1) which is connected at its rear end to a lever 76 having a roll 77 engaged by a side face groove in a cam 78. The cam 78 is mounted on the usual bottom shaft 79 of the loom, which makes one revolution for each two beats of the lay.

As it may be necessary to operate the transferrer upon any beat of the lay, the cam 78 is provided with two actuating portions 80, disposed at opposite ends of a diameter of the cam. Whenever any one of these a tuating portions 80 engages the cam roll 77, the rod 70 is given a quick rearward movement in the recess 69 of the plunger or support 66.

In normal operation, this reciprocation of the actuating rod 70 is entirely idle and produces no result. I have provided means, however, for operatively connecting the rod 70 with the plunger 66 to cause rearward transferring movement of the transferrer 32. For this purpose, a bearing sleeve 82 (Fig. 2) is fixed in one side of the plunger 66 and projects downward through a slot 130

83 in the bearing 67. This sleeve 82 prevents angular displacement of the plunger 66 and also provides a bearing for a stud 84 having a head 85 at its upper end. Re-cesses 86 are formed in the upper part of the plunger 66 and in the upper part of the bearing 67, to permit the headed stud 84 to be dropped into its bearing sleeve 82. A coil spring 87 normally seats the stud 84 against the end of the sleeve 82, with the head depressed below the path of the actuating rod 70. The spring 87 is disposed between the lower end of the sleeve 82 and a collar 88 secured on the stud 84.

15 A cap 90 at the upper end of a rod 91 (Fig. 2) is positioned below the stud 84 when the latter is in normal forward position. The rod 91 is vertically slidable and is pivoted at 92 to a lever 93 mounted on a 20 fixed pivot 94 and having a forwardly projecting portion 95 (Fig. 1), pivoted at 96 to an arm 97 mounted on an indicating shaft or rod 98.

The shaft 98 extends across the front of 25 the loom to the left hand side, where it may be selectively connected to suitable actuating mechanism by weft detecting mechanism of any suitable type, such as is indicated in the prior application of Gordon, Serial No. 30 83,859, filed Jan. 26, 1926.

When the weft detecting mechanism indicates substantial weft exhaustion, the shaft 98 will be rocked, thus raising the rod 91 and the cap 90 against the lower end of the 35 stud 84, and projecting the stud upward into the path of the rod 70. When engaged by the rod, the stud will move rearward with the plunger 66.

The rod 70 is provided with a shoulder 99 40 (Fig. 2) adapted to be engaged below the head 85 of the stud 84, thus holding the stud in raised position until released by extreme forward movement of the rod 70. The cap 90 is threaded to the upper end of the rod 45 91, so that it may be vertically adjusted thereon, and a lock nut 100 is provided for holding the cap in adjusted position. A turn buckle 101 (Fig. 1) is provided in the link 75 for adjusting the forward and rearward movement of the rod 70.

I have thus provided actuating means having a regular rearward movement for every beat of the lay, and I have provided connections controlled from the weft detecting 55 mechanism by which the actuating means may be operatively connected to the plunger 66 and transerrer 32.

Co-ordinating mechanism.

60 I have described mechanism for bringing the discharge opening of a selected magazine compartment opposite the shuttle about to become active, and mechanism for moving the transerrer to a similar position. These 65 movements take place before the movement

of the selected shuttle box to running position, and it is therefore necessary to provide co-ordinating mechanism by which the magazine and transerrer will be maintained in operative relation to the selected shuttle 70 box during the movement of the box.

For this purpose I have pivoted a pinion 105 (Fig. 3) on a stud 106 fixed in the stand 43. The pinion is actuated by a rack bar 107 vertically slidable in the stand 43 and 75 having a stud 108 pivoted to the upper end of an actuating link 109. At its lower end, the link 109 (Fig. 1) is pivoted to a rock-arm 110 mounted upon a rock shaft 111 extending across to the left hand side of 80 the loom and operatively controlled by the drop box mechanism, as will be hereinafter described.

The lifter rod 22 for the boxes 21 previously described is provided with a head or 85 bracket 112 (Fig. 1) at its lower end, which is pivotally connected to the same stud 113 at the end of the arm 110 on which the link 109 is pivoted. The drop boxes 21 and the rack bar 107 thus receive equal and 90 simultaneous vertical movements, the movement of the rack bar causing corresponding rotation of the pinion 105.

The pinion 105 engages rack teeth 115 on a rack member 116 vertically slidable in 95 guide-ways in the stand 43, and the member 116 is provided with rack teeth 117 engaging the pinion 45 previously described, and also with rack teeth 118 engaging the pinion 57 previously described.

The positioning links 47 and 60 receive their operative movements before the co-ordinating link 109, so that the pinions 45 and 57 are maintained in fixed vertical position during the movement of the sliding rack member 116, which therefore rotates the pinions 45 and 57 and causes vertical movement of the supports 41 and 54 for the magazine and transerrer, which movements are in the same direction and of equal 105 amount to the movements of the drop boxes 21.

I am thus able to bring the transerrer and any desired magazine compartment opposite its associated shuttle box and to thereafter move the box, the magazine, and the transerrer simultaneously vertically to maintain their operative relation and to permit transfer of the weft carrier during movement of the shuttle box to running 110 position. This provision for a longer time 120 interval for transfer is extremely important.

Pattern mechanism.

I will now describe the pattern mechanism and connections by which the magazine, the transerrer, the weft detector, and the shuttle boxes are selectively controlled and positioned.

Referring particularly to Figs. 5 to 11, 130

I have indicated pattern chains 120 and 121 (Fig. 5) mounted on a pattern cylinder having a star wheel 122 secured to the end thereof and engaged by pins 123 on a rotating actuating member 124. The member 124 makes one revolution for each beat of the lay and the pins 123 are diametrically opposed. The star wheel 122 is thus intermittently and successively advanced two spaces for each beat of the lay.

Pattern levers are engaged by the chains 120 and 121, and the sinkers and risers on the pattern chains are so distributed that a change in position of the levers for the chain 120 will occur on certain advance movements of the star wheel, while a change in position of the remaining levers will occur on the alternate advance movements of the star wheel. The first set of pattern levers controls the movements of the weft detector, the magazine and the transerrer, and the second set of pattern levers controls the movements of the drop boxes and the co-ordinating movement of the magazine and transerrer therewith.

The mechanism controlled by the levers 125 is in general of the usual type and need be only briefly described. The pattern levers 125 (Fig. 5) are connected by links 126 to vibrator levers 127, supporting vibrator gears 128 which may be raised or lowered to engage upper or lower cylinder gears 129 or 130, all as usual. The vibrator gears 128 are connected by links 131 to the upwardly extending arms of bell cranks 132 and 133 mounted on a fixed pivot 134.

An outer pair of bell cranks 132 and 133, as viewed in Figs. 5 and 6, are connected by links 135 and 136 to a floating lever 137, connected by a link 138 to an arm 139 on a rock shaft 140. The rock shaft extends across the loom and at its opposite end is provided with an arm 141 (Fig. 1) connected by a link 142 (Fig. 13) to the rocking member 49 by which the magazine M and transerrer 32 are vertically positioned.

The second pair of bell cranks 132 and 133 are connected by links 145 and 146 (Fig. 6) to a floating lever 147 having a link 148 by which the vertical position of the weft detector, not shown, is varied in accordance with the position of the drop boxes and the selection of the running shuttle.

The third pair of bell cranks 132 and 133 are connected by forked links 150 and 151 (Fig. 6) to a floating lever 152 having a stud 153 at its front end. Two links 154 and 155 are pivoted on the stud 153, the link 154 raising and lowering the drop boxes in the usual manner and the link 155 being connected to maintain the weft detector in co-ordinate relation with the selected shuttle box as the boxes are raised or lowered. Slotted brackets 157 are engaged by pins 158 on the floating levers and cause the

front ends of said levers to have a substantially straight line movement.

An arm 156 on the rock shaft 111 previously described, is connected at its front end to the stud 153, thus transmitting the motion to the right hand side of the loom and causing the drop boxes at both ends of the lay to be moved simultaneously, and also causing the magazine and transerrer to move with the drop boxes, as previously described.

The vibrator levers are necessarily locked as usual in raised or lowered position during the operation of the cylinder gears, and lock knives or bars 160 and 161 (Fig. 10), are provided for locking the vibrator levers. As the levers connected with the weft detecting magazine move a step in advance of the levers which control the drop boxes, it is necessary to provide a separate locking bar for each set of levers, and to operate these locking bars alternately.

Accordingly I have provided two cams 162 and 163 (Fig. 9) on the pattern cylinder shaft, these cams being set approximately 180° apart. Each cam is engaged by a cam roll 164 on a rod or projection 165 connected to locking bars 160 and 161. Spring pressed rods 166 (Fig. 5) force the locking bars forward to locking position.

The relative timing of the two sets of pattern mechanism also requires that the cylinder gears 129 and 130 have idle and driving portions arranged in alternate positions. A portion of the cylinder gear 130 is shown in Fig. 9, in which it will appear that the driving teeth 170 for the drop boxes are positioned on one side of the gear, while the teeth 171 for the weft detector and transfer mechanism are disposed substantially 180° in advance of the teeth 170.

General operation.

Having described the details of construction of my improved loom, the general operation is thought to be clearly apparent. The chains of the pattern mechanism P are constructed with risers and sinkers in the desired order to position the weft detector opposite the shuttle box at the left hand side of the loom which is about to become operated, while at the same time, the transerrer and magazine compartment corresponding to the same shuttle are moved to positions opposite the corresponding shuttle box at the right hand or magazine side of the loom. When weft exhaustion is indicated, the stud 84 is raised by the mechanism shown in Fig. 2 to a position for engagement by the actuating rod 70, the transerrer 52 being thereafter moved rearwardly to transfer a weft carrier from the magazine to the exhausted shuttle.

During the transfer operation, the shuttle boxes may be raised or lowered to bring the

selected shuttle box to running position, but through the connections shown in Figs. 2 and 3, the selected magazine compartment and the transerrer are maintained in operative relation with the selected shuttle box, the transfer taking place while the box is being moved to running position.

All parts of the mechanism are strongly and rigidly constructed and are well adapted 10 to stand up under the severe conditions of loom operation. The movements are positive and the device is particularly effective for the purposes indicated.

Having thus described my invention and 15 the advantages thereof, I do not wish to be limited to the details herein disclosed otherwise than as set forth in the claims, but what I claim is:—

1. In an automatic loom having a lay and 20 a plurality of shifting shuttle boxes at both ends thereof, in combination, a magazine having compartments for weft carriers of different kinds, means to move a selected compartment opposite a selected shuttle box, 25 and means to thereafter move said compartment with said shuttle boxes as the selected box is moved to running position.

2. In an automatic loom having a lay and 30 a plurality of shifting shuttle boxes at both ends thereof, in combination, a magazine having a plurality of vertically disposed compartments for weft carriers of different kinds, means to move a selected compartment opposite a selected shuttle box, and means 35 to thereafter move said compartment with said shuttle boxes as the selected box is moved to running position.

3. In an automatic loom having a lay and 40 a plurality of shifting shuttle boxes at both ends thereof, in combination, a magazine having a plurality of vertically disposed compartments for weft carriers of different kinds, each compartment having a rearward discharge opening, means to move 45 a selected compartment to bring its discharge opening opposite a selected shuttle box, and means to thereafter move said compartment with said shuttle boxes as the selected box is moved to running position.

4. In an automatic loom having a lay and 50 a plurality of shifting shuttle boxes at both ends thereof, in combination, a magazine having a plurality of vertically disposed compartments for weft carriers of different kinds, pattern-controlled means to move a selected compartment opposite a selected shuttle box, and pattern-controlled means 55 to thereafter move said compartment with said shuttle boxes as the selected box is moved to running position.

5. In an automatic loom having a lay and 60 a plurality of shifting shuttle boxes at both ends thereof, in combination, a magazine having weft carriers of different kinds separately stored therein, means to move said

magazine vertically to position a weft carrier of a selected kind opposite a shuttle about to become active, and means to thereafter move said weft carrier vertically with said shuttle as the latter moves to running 70 position.

6. In an automatic loom having a lay and a plurality of shifting shuttle boxes at both ends thereof, in combination, a magazine having weft carriers of different kinds separately stored therein, means to move said magazine vertically to position a weft carrier of a selected kind opposite a shuttle about to become active, means to thereafter move said weft carrier vertically with said 75 shuttle as the latter moves to running position, and means to transfer said weft carrier as the shuttle is being moved vertically.

7. In an automatic pick and pick loom having a lay and a plurality of shifting shuttle boxes at both ends thereof, in combination, a magazine having weft carriers of different kinds separately stored therein, means to move said magazine vertically to position a weft carrier of a selected kind opposite a shuttle about to become active, means to align a transerrer with said weft carrier and shuttle, and means to maintain operative relations between said transerrer, 80 said weft carrier, and said shuttle, as said shuttle is shifted to running position.

8. In a pick and pick loom, having a plurality of vertically shifting shuttle boxes, at each side of the loom, a weft carrier magazine having a plurality of superposed compartments each having a rearward discharge opening, and pattern-controlled means to raise or lower said magazine relative to the boxes at the magazine side of the loom to bring a selected discharge opening to delivery position with respect to a selected shuttle box.

9. In a pick and pick loom, having a plurality of vertically shifting shuttle boxes, at each side of the loom, a weft carrier magazine having a plurality of superposed compartments each having a rearward discharge opening, and pattern-controlled means to raise or lower said magazine relative to the boxes at the magazine side of the loom to bring a selected discharge opening to delivery position with respect to a selected shuttle box and means to thereafter move said magazine vertically with said boxes to maintain such relation as the boxes are 110 moved.

10. In a loom, a lay having a plurality of shifting shuttle boxes at each end thereof, a weft carrier magazine having a plurality of compartments superposed in a single plane 125 and each having a rearward discharge opening, said magazine being adapted to contain and deliver weft carriers of distinctive colors from said different compartments, means to move said magazine vertically in 130

definite relation to the vertical movement of the shuttle boxes at the magazine end of the lay, and means to transfer a weft carrier rearward from a selected compartment directly into the shuttle corresponding in weft color thereto.

11. In a loom, a magazine, a transerrer, means to move said magazine and transerrer in opposite directions, and means to move said magazine and transerrer in the same direction.

12. In a loom, a magazine, a transerrer, a single means to move said magazine and transerrer in opposite directions, and additional means to move said magazine and transerrer in the same direction.

13. In a loom, a magazine, a transerrer, means to move said magazine and transerrer in opposite directions, and means to move said magazine and transerrer in the same direction, said moving means including rack bars connected to said magazine and transerrer, pinions engaging said rack bars and selectively movable transversely of their axes by pattern-controlled means, an additional rack bar engaging said pinions, and pattern-controlled means for moving said latter rack bar.

14. In a loom, a magazine, a transerrer, means to move said magazine and transerrer in opposite directions, and means to move said magazine and transerrer in the same direction, said moving means including rack bars connected to said magazine and transerrer, pinions engaging said rack bars and selectively movable transversely of their axes by pattern-controlled means, an additional rack bar engaging said pinions, and pattern-controlled means for moving said latter rack bar, said first-mentioned rack bars remaining fixed in position while said additional rack bar is moved.

15. In an automatic "pick and pick" loom, a movable weft detector, magazine and transerrer, pattern mechanism operative to move said detector, magazine and transerrer to operative relation with the shuttle about to become active, and pattern-controlled means to thereafter move said parts with said shuttle to running position.

16. In an automatic "pick and pick" loom, a vertically movable weft detector, magazine and transerrer, pattern mechanism operative to move said detector, magazine and transerrer vertically to operative relation with the shuttle about to become active, and pattern-controlled means to thereafter move said parts vertically with said shuttle to running position.

17. In an automatic "pick and pick" loom, a movable weft detector, magazine and transerrer, pattern mechanism operative to move said detector, magazine and transerrer to operative relation with the shuttle about to

become active, and pattern-controlled means to thereafter move said parts with said shuttle to running position, said successive movements being separated by substantially one-half a revolution of the loom crank shaft.

18. In an automatic "pick and pick" loom, a movable weft detector, magazine and transerrer, pattern mechanism operative to move said detector, magazine and transerrer to operative relation with the shuttle about to become active, and pattern-controlled means to thereafter move said parts with said shuttle to running position, said pattern mechanism being advanced to a new indicating position at each one-half revolution of the loom crank shaft.

19. In an automatic "pick and pick" loom, a movable weft detector, magazine and transerrer, pattern mechanism operative to move said detector, magazine and transerrer to operative relation with the shuttle about to become active, and pattern-controlled means to thereafter move said parts with said shuttle to running position, said pattern mechanism being advanced to a new indicating position at each one-half revolution of the loom crank shaft, and mechanism being provided to separately lock said pattern mechanism and said pattern-controlled means after each advance movement of either one.

20. In a loom, a transerrer having a recessed member connected thereto, an actuator intermittently reciprocated in said member, and a weft-controlled connecting element between said member and said actuator.

21. In a loom, a transerrer having a recessed member connected thereto, an actuator intermittently reciprocated in said member, a connecting cross pin in said member, and weft-controlled means to move said pin into the path of said actuator.

22. In a loom, a transerrer having a recessed member connected thereto, an actuator intermittently reciprocated in said member, a connecting cross pin in said member, and weft-controlled means to move said pin into the path of said actuator, said actuator having a projecting portion at the engaging end thereof and said cross pin having a head engaged by said projecting portion and held in operative relation thereby.

23. In a loom, a frame, a casing fixed to said frame, a pair of slide bars vertically movable in said casing, a magazine supported by one slide bar, a transerrer supported by the other slide bar, and means to actuate said bars to move said magazine and transerrer vertically.

24. In a loom, a frame, a casing fixed to said frame, a pair of slide bars vertically movable in said casing, a magazine supported by one slide bar, a transerrer sup-

ported by the other slide bar to move said magazine and transerrer simultaneously in opposite directions to a common operating position.

5 25. In a loom, a frame, a casing fixed to said frame, a pair of slide bars vertically movable in said casing, a magazine sup-

ported by one slide bar, a transerrer supported by the other slide bar, said means being under the control of regularly actuated pattern mechanism. ¹⁰

In testimony whereof I have hereunto affixed my signature.

SAMUEL A. NELSON.
